UNITED STATES PATENT OFFICE.

WALTER B. SCHULTE, OF MADISON, WISCONSIN, ASSIGNOR TO BURGESS BATTERY COMPANY, A CORPORATION OF WISCONSIN.

DRY CELL.

1,342,001.

Specification of Letters Patent.

Patented June 1, 1920.

Application filed August 26, 1918. Serial No. 251,367.

To all whom it may concern:

Be it known that I, WALTER B. SCHULTE, a citizen of the United States, residing at Madison, in the county of Dane, State of Wisconsin, have invented certain new and useful Improvements in Dry Cells; and I do hereby declare the following to be a full, clear, and exact description of the invention, such as will enable others skilled in the art to which it appertains to make and use the same.

The present invention relates to improvements in dry cells, and more particularly in the terminals thereof; and it primarily resides in the provision of a specially-constructed terminal which may be attached to the zinc can or electrode in a more secure and effective manner than has heretofore been possible, and in such a way as to lie wholly within the plane of the can, so that a number of cells may be arranged side by side for transportation or other purposes with their cartons actually touching one another, but with no danger whatever of contact between the terminals of adjacent cells.

The invention further comprises an improved attachment for the contact screw or terminal of the carbon electrode, the attachment consisting of a spring washer or its equivalent, which is fitted on the aforesaid terminal and bears against the metal cap associated with the same. By virtue of this arrangement, the terminal will be securely held in place, consequent upon the tightening of the washer against the cap by the binding nut, thereby insuring efficient contact between it and the electrode.

The invention also comprehends the provision of a metal guard ring, which fits over and reinforces the upper end of the zinc can, and which, in conjunction with a label held in place thereby, serves to protect the pitch or other seal against breakage, and the zinc terminal against accidental detachment.

With the above and other objects in view, the invention consists in the construction, combination and arrangement of parts as shown and described in the following specification, illustrated in the accompanying drawing, and particularly set forth in the appended claims. The said drawing discloses what may be regarded for all present purposes as the preferred form of the in-

vention; but the latter is not to be considered as limited to the precise details of such disclosure, excepting in so far as may be necessary from the terms of the claims, since modifications and changes may well be made within the scope thereof, and parts of the invention may be utilized without others, and in other and different environments.

In the drawing:

Figure 1 is a broken, part-sectional side elevation of a dry cell or battery constructed in accordance with the invention;

Fig. 2 is a plan view;

Fig. 3 is a plan view of the cell proper, with the guard, binding nuts and spring washer omitted;

Fig. 4 is an enlarged detail view, showing the mounting of the terminal of the zinc electrode;

Fig. 5 is a perspective view of said terminal;

Figs. 6 and 7 are similar views of the guard and label, respectively;

Fig. 8 is a perspective view of the spring washer; and

Fig. 9 is a fragmental, part-sectional side elevation of an arrangement in which the guard and label are omitted.

Referring more particularly to said drawing, 1 indicates the pasteboard or other carton which contains the cell or battery, 2 the zinc can, cup or electrode, 3 the carbon electrode, and 4 the pitch or equivalent seal. All of these parts are, or may be, of conventional type, and, hence, require no extended description. The carbon electrode 3 is in the form of a rod, as usual, and is equipped at its upper end with a brass cap 5, which fits thereover and is partly embedded in the seal, this part and the associated screw or binding post 6 likewise being of more or less conventional form. The said screw or post is provided with an enlarged head 7, which rests upon the top face of the rod and is formed with a rectangular boss 8 fitting in a correspondingly-shaped opening in the cap and serving to prevent rotation of the screw, the aforesaid head being somewhat larger than its boss, so that a portion of the cap thus overlies the head 100 and tends to hold the post in vertical position. The threaded stem of the post carries the usual binding nut 9, which is adapt-

ed to clamp a conducting wire (not shown) against the cap, or against an interposed washer, in the ordinary manner.

It frequently happens, however, that the screw terminal or post works loose in one way or another, with the result that the electrical contact between its head and the carbon rod is impaired. To offset this, I provide the improved spring washer 10, previously mentioned, said washer taking the place of the usual flat washer and acting to maintain the post in upright position with its head resting squarely against cap 5. In its preferred form, the spring washer 15 consists of a thin disk of metal which is stamped or pressed into the shape of a dish or shallow cup, as shown, the free edge of the cup resting upon the top of the cap, while its flat top is provided with a central 20 perforation 11 for the extension of the post therethrough. By reason of this arrangement, it results that when pressure is imposed upon the washer, due to the tightening of the nut 9, the said washer will be expanded and caused to bind against the cap and, hence, will prevent the post from tilting, so that its head is necessarily held in effective contact with the cap.

The terminal associated with the zinc can 30 or electrode presents the most important features of the invention, and, in its preferred form, consists of upper and lower vertical portions 12 and 13, and an integral horizontal, central portion 14 connecting them, the two portions 12 and 13 being arranged in offset relation with respect to each other. The lower portion 13, which constitutes the stem of the terminal, is designed to fit in a vertical recess, indentation or 35 pocket 15, formed in the upper end of the zinc can, as clearly indicated in Fig. 4. This pocket has a length somewhat greater than that of the stem 13, and a width at least as great as the diameter of said stem, from 40 which it follows that the solder 16 which is used to fasten the stem to the can will be enabled to flow into and fill the spaces between the side walls of the pocket and the surface of the stem, besides covering the entire front of the stem, and will also fill 45 part or all of the pocket below the stem, so that a greatly enlarged contact area is provided in this way for the solder, and the rigidity of the joint correspondingly increased.

As further regards the mounting of the stem in the pocket, as above described, it is an important feature thereof that the said stem lies entirely within the plane of the 50 circumference of the can, due to the depth of the pocket, so that after the soldering operation has been completed, the can, with the terminal thereon, may be readily inserted into, or withdrawn from, the carton, 55 without any interference on the part of the

stem; and, when in place in the carton, the latter will not be bulged outward by the said stem, which might tend to rupture the carton, and, in any event, would preclude the cells from being stacked or arranged 70 side by side with their cartons in contact throughout their entire length.

The connecting piece 14 between the stem and threaded portions 13 and 12 of the zinc terminal extends inwardly toward the center of the can; and by reason of that fact, the last-named portion or member 12 will be disposed inwardly of, and, hence, out of alignment with, the first-named or stem portion or member 13. Consequently, the said 75 threaded portion will be disposed within the confines of an imaginary cylindrical surface or plane forming a continuation of the plane of the carton, so that when a number of cells are arranged side by side in contact, the 80 terminals of adjacent cells will be prevented from engaging one another. The above-mentioned connection 14 is designed to project across and rest upon the upper edge of the zinc can, and in this way serves to position the stem portion of the terminal in its pocket, said portion 14 also forming a support for the lower of a pair of metal washers 85 17 carried by the threaded portion 12, between which washers a nut 18 is interposed, 90 and above which is mounted a binding nut 19.

The cell is completed by a guard 20 and label 21, which act conjointly to strengthen the can at its upper end and to protect the 100 pitch seal 4 against breakage, as hereinafter explained, the guard also serving to protect the soldered joint between the stem of the offset terminal and the zinc can; but while these parts are preferably included in the 105 cell, they are not absolutely essential, and may, if desired, be omitted, as will be understood from Fig. 9; the construction therein represented being in all other respects identical with that above described. The guard 110 20 may advantageously consist of a metal ring, which is formed at its upper edge with an in-turned flange 22 having a perforation 23 therein, the flange being slightly widened at the point where the perforation is located, 115 as clearly shown in Fig. 6. This ring is designed to snugly encircle the upper end of the can, so that it extends across the front of the pocket 15 and the soldered stem portion 13 of the aforesaid offset terminal and serves 120 to protect the joint against accidental injury, as well as to strengthen the can at its top; and since the height of the ring is at least as great as the depth of the pitch seal, the latter likewise will be protected.

The label 21 may be constructed of pasteboard or other suitable material, and may bear any desired printing on its outer face, for advertising or other purposes. It is designed to rest upon the outer face of the 125 130

pitch seal, which it completely covers; and it is formed with an inwardly-extending peripheral notch 24 and with a central opening 25, through which the metal cap 5 projects. The edge portion of the label underlies the flange 22 of the guard ring 20, and its notch 24 is disposed directly beneath the perforation 23 in said flange, so that the connecting portion 14 of the offset terminal 10 is thus enabled to fit in said notch and, consequently, serves to hold the label against turning movement, as will be understood from Fig. 1. The threaded portion 12 of said terminal projects upwardly through the 15 perforation 23.

The invention, its structural features and advantages, are believed to be apparent from the foregoing, and further description and explanation thereof being accordingly 20 omitted.

I claim as my invention:

1. In a battery having a zinc electrode in the form of a fluid tight cup or container, a contact terminal fixed directly against the 25 wall of said cup at the upper end thereof and disposed within the confining plane of the cup.

2. In a battery having one electrode in the form of a cup or container, a contact terminal attached directly to said cup and comprising an offset threaded binding post disposed within the confining plane thereof.

3. In a battery having one electrode in the form of a thin cup or container, a pocket 35 pressed into the upper end of the wall of said cup, and a contact terminal comprising a stem portion secured in said pocket and an exposed portion offset inwardly with relation to said stem to lie within the confining 40 plane of the cup.

4. In a battery having one electrode in the form of a thin cup or container, a pocket in the upper end of the wall of said cup, and a contact terminal comprising a stem portion secured in said pocket, a binding post integral with and disposed above said stem, and a flat connecting portion between said stem and post and resting upon the upper edge of said pocket, said post being offset 50 inwardly with relation to said stem to position it within the confining plane of the cup.

5. In a battery having one electrode in the form of a cup or container, and a seal in the upper end thereof, a pocket in the sealed 55 end of said electrode, a contact terminal having its stem secured in said pocket, and a metal reinforcing ring encircling said sealed end to strengthen the same and protect the seal against breakage, said ring extending across said pocket and the stem 60 therein.

6. In a battery, an electrode in the form of a cup or container, having the outer sur-

face of its wall indented at the upper end thereof to provide a pocket, a seal in said 65 end, a contact terminal having its stem secured in said pocket, and a guard ring encircling said sealed end to strengthen the same and protect the seal against breakage, said ring extending across said pocket and 70 the stem therein.

7. In a battery, an electrode in the form of a cup or container having a pocket in its upper end, a seal in said end, a metal ring encircling said sealed end to strengthen the 75 same and protect the seal against breakage, and extending across said pocket, said ring having its upper edge turned continuously inward so as to overlie said seal and provided with a perforation, and a contact terminal comprising a stem portion secured in said pocket and a binding post extending 80 upwardly through said perforation.

8. In a battery, an electrode in the form of a cup or container having a pocket in its 85 upper end, a seal in said end, a metal ring encircling said sealed end to strengthen the same and protect the seal against breakage and extending across said pocket, said ring having a continuous, in-turned rim which 90 overlies the seal and is provided with a perforation, and a contact terminal comprising a stem secured in said pocket, a horizontal portion on the upper end of said stem underlying said rim directly beneath said perforation, and a binding post on said horizontal portion projecting upwardly through 95 said perforation.

9. In a battery, an electrode in the form of a cup or container having a pocket in its 100 upper end, a seal in said end, a metal ring encircling said sealed end to strengthen the same and extending across said pocket, said ring having a continuous rim which projects inwardly over the seal and is provided with a perforation, a label resting upon said seal with its edge underlying said rim and having a radial notch which directly underlies said perforation, said label and ring acting conjointly to protect said 105 seal against breakage, and a contact terminal comprising a stem portion secured in said pocket, a lateral connecting portion at the upper end of said stem fitting in said notch, and a binding post on said connecting 110 portion projecting upwardly through said perforation.

10. A battery terminal of unitary construction embodying a lower rod-like portion or stem, a threaded cylindrical upper 120 portion integral therewith and offset with respect thereto and a flat connecting portion between said upper and lower portions, substantially as described.

In testimony whereof I affix my signature. 125
WALTER B. SCHULTE.
